UNITED STATES PATENT OFFICE

2,514,142

HYDRAULICALLY DRIVEN OSCILLATORY
BRUSH

John D. Reid, Oak Ridge, Tenn., assignor, by
mesne assignments, to the United States of
America as represented by the United States
Atomic Energy Commission.

Application January 5, 1945, Serial No. 571,433

2 Claims. (Cl. 15—22)

1

This invention is concerned with cleaning or scrubbing means and is particularly directed to a power operated brush for cleaning or scrubbing surfaces.

A primary object of the invention is to provide a cleaning or scrubbing device utilizing water or other cleaning fluid and which is so constructed and arranged that the cleaning fluid is entirely recovered or saved after the cleaning operation has been effected. The purpose to be achieved by this objective is that of cleaning or scrubbing a surface with a cleaning fluid which dissolves certain materials from the surface and which may then be recovered later from the cleaning fluid or medium by chemical recovery processes.

Another object of my invention is to provide a cleaning device consisting of a scrubbing brush having a housing around the brush which can be held in contact with the surface to be cleaned in fluidtight relationship therewith and the housing having a connection thereto whereby the cleaning medium or fluid and air can be withdrawn from within the housing and saved.

Another object of the invention is to provide a device as in the previous object wherein the power operating means is a device operated by the cleaning fluid or medium which is supplied under pressure to the operating means and then to the brush or other cleaning element itself.

Another object of the invention is to provide a power operating means for an automatic brush or the like consisting of a vane arranged to oscillate in response to fluid under pressure supplied alternately to the opposite sides of the vane.

Further objects and numerous of the advantages of my invention will become apparent from the following detailed description and annexed drawing wherein:

Fig. 1 is a sectional view of the device of my invention taken along the line 1—1 of Fig. 2.

Fig. 2 is another sectional view of the invention taken along the line 2—2 of Fig. 1.

Referring to the drawings, the device comprises a cylinder or cylindrical block member 1 which can be seen on both figures, and this member fits within a circular shield or skirt 2 which surrounds the scrubbing element. The scrubbing element consists of a commercial brush 3 which is a circular device, that is, it is round, and it is mounted on an axle or spindle 4 which is journaled centrally in the member 1 as shown. The brush 3 is attached to a screw threaded nipple at the right end of member 4 by means of a nut 5 as shown. A plate 6 is attached to the left face of member 1 by acorn nuts as shown.

2

As will be described below, in the operation of the apparatus the brush is oscillated back and forth through an angle of 60° for scrubbing while at the same time water is admitted through a longitudinal bore in the axle of the brush, and is then dispersed through the brush by centrifugal force; both water and air are withdrawn from the vicinity of the brush through a vacuum connection.

At the right end of the skirt 2, a brass rod 6 is soldered to the skirt all the way around and fitted over the brass rod is split rubber tubing indicated by the numeral 7. The device in operation is held against the surface of the tank wall with the rubber tubing 7 forming a bearing surface.

The member 1 has a sector cut away as may be seen in the upper part of the figures, this being designated by the numeral 8 and within this cut-away area a vane 9 oscillates back and forth through 60° to operate the brush 3, the bottom part of the vane 9 fitting in a slot in the spindle 4 as may be seen on Fig. 1.

The vane 9 is caused to oscillate back and forth by the pressure of the water which is supplied to the brush as will be described. Water may be admitted to the cutaway 8 on either side of the vane 9 through channels 11 and 12 in the member 1. The channels 11 and 12 communicate with a sleeve valve designated generally by the numeral 13.

The valve 13 comprises a sliding member 14 which slides in a channel cut transversely in the member 1; the valve member 14 has channels 15 and 16 cut transversely therein, and these channels can be brought into registry with the channels 12 and 11 respectively when the valve member 14 is moved to the right and to the left. Channels 15 and 16 can also be brought into registry with channels 17 and 18 in the member 1 which align with channels 12 and 11 respectively, the channels 17 and 18 being connected to tubes 19 and 20 which connect to a Y connection 21, the source of water supply being connected to the Y connection.

The valve member 14 also has angular channels 22 and 23 in a V-shape which cooperate with channels 24 and 25 cut in the member 1 and forming a V, the two channels 24 and 25 connecting with a tube 26 which forms a water outlet. When the valve member 14 is moved to the right as shown in Fig. 1, channel 23 connects 11 with 25 and when member 14 is moved to the left 22 connects 12 and 24.

Thus, with the parts in the position shown in Fig. 1, water can only be admitted through 19, and then through 17, 15, and 12 to the left side of vane 9 for moving the brush

clockwise. With the parts in this position, water on the right side of vane 9 escapes through 11, 23, 25, and 26.

The spindle 4 has a pin 30 as shown in Fig. 2 which extends down therefrom and which oscillates therewith. Pin 30 is disposed between two pins 32 which extend to the left as seen on Fig. 2 from member 14, and as spindle 4 oscillates, pin 30 cooperates with pins 32 moving the valve member 14 back and forth so as to admit water alternately to opposite sides of vane 9 so as to cause the vane to oscillate as described and to similarly cause the brush 3 to oscillate.

The water supply to the brush is through two longitudinal bores 33 and 34 in the spindle 4 which are in communication with opposite sides of the vane 9 by channels 35 and 36. Thus, the water can at all times pass from either side of the vane 9 through the channels 35 and 36, and the bores 33 and 34 to the center of the brush where it is dispersed or diffused by centrifugal force. As described above, water and air are withdrawn from within the skirt 2 by way of vacuum connection 40.

From the foregoing it can be seen that the device described can be held against a surface with the tubing 7 bearing against the surface so that the interior of the housing formed by skirt 2 is substantially fluidtight so that the water or other medium used for cleaning purposes can all be saved by withdrawing it through the connection 40. Thus, any matter which becomes suspended in the cleaning medium or dissolved therein can later be recovered therefrom by various chemical or other recovery processes.

Those skilled in the art will observe that my invention provides an efficient device wherein the desired purposes are achieved and cleaning can be effectively done by reason of the rapid oscillatory motion of the brush. The pressure of the water or other cleaning medium used is utilized as the source of power for operating the brush.

The foregoing description of my invention is representative of its preferred form and it is intended that the disclosure be interpreted in an illustrative rather than a limiting sense. It is intended that the boundaries of the invention be determined in accordance with the scope of the claims appended hereto.

I claim:

1. A cleaning device of the character described comprising in combination, means forming a brush adapted for scrubbing a surface, fluid operated means for said brush for causing the brush to move in scrubbing relationship with the surface, said last means comprising a shaft, a vane rigidly mounted on said shaft and means whereby fluid under pressure is alternately admitted to and removed from opposite sides of the said vane to cause it to oscillate and move said shaft, said brush being mounted on said shaft adjacent one

end thereof, and means forming a housing around the brush constructed and arranged so as to adapt it to be held against a surface so that the brush is in contact with the surface and the engagement between the housing and the surface is substantially fluidtight and means for conducting said fluid through the brush to the interior of the housing and withdrawing it therefrom.

2. A cleaning device of the character described comprising in combination, means forming a brush adapted for scrubbing a surface, power operating means for said brush for causing the brush to move in scrubbing relationship with the surface, said last means comprising a shaft, a vane carried on said shaft and means whereby fluid under pressure is alternately admitted to opposite sides of the said vane to cause it to oscillate said shaft, said brush being mounted on said shaft and means forming a housing around the brush constructed and arranged so as to adapt it to be held against a surface so that the brush is in contact with the surface and the engagement between the housing and the surface is substantially fluidtight and means for admitting a fluid to the interior of the housing and withdrawing it therefrom, said last means comprising passageways formed in said shaft and communicating with the opposite sides of said vane so that the fluid which operates the vane is conveyed through the shaft and discharged substantially centrally through the brush, and provides the cleaning medium.

JOHN D. REID.
